(57) **CLAIM**

The ornamental design for a user interface for ultrasound device, as shown and described.

DESCRIPTION

FIG. 1 is a perspective view of a user interface for ultrasound device embodying the new design;

FIG. 2 is an enlarged view of a portion in region labeled 2 of FIG. 1;

FIG. 3 is a right side view of the design, the left side view being a mirror image thereof;

FIG. 4 is a front view thereof;

FIG. 5 is a rear view thereof;

FIG. 6 is a top view thereof;

FIG. 7 is an enlarged view of a portion in region labeled 7 of FIG. 6; and,

FIG. 8 is a bottom view thereof.

The portions shown in broken lines in FIGS. 1-8 are shown for environmental purposes and form no part of the claimed design. The broken lines immediately adjacent the solid lines form the boundary of the claimed design.
